UNITED STATES PATENT OFFICE.

WILLIAM F. DEISTER, OF FORT WAYNE, INDIANA.

SLIME-CONCENTRATOR.

1,071,714.

Specification of Letters Patent.

Patented Sept. 2, 1913.

Application filed July 6, 1911. Serial No. 637,219.

To all whom it may concern:

Be it known that I, WILLIAM F. DEISTER, residing at Fort Wayne, in the county of Allen and State of Indiana, a citizen of the 5 United States, have invented or discovered certain new and useful Improvements in Slime-Concentrators, of which improvements the following is a specification.

It is characteristic of tables for treating 10 slime that they have a slight down inclination from the point or edge at which the pulp or slime is fed into the same. It is customary that the surface of the table over which the slime flows should be provided 15 with "waves", such waves being usually formed by ribs over which the fabric forming the surfaces of the table is laid. Heretofore these ribs, the function of which is to catch the values as they settle out of the 20 slime and direct such material toward a portion of the edge of the table out of the line of flow of the gangue or tailings, have been arranged in lines at right angles or so nearly at right angles to the initial direction 25 of flow of the pulp or slime hence the movement of the values or concentrates along the upper sides of the "waves" is very slow even when the movement thereof is accelerated by vibrating the tables.

30 The invention described has for its object an arrangement of waves relative to the initial direction of flow of the pulp and also the direction of vibration of the table whereby the movement of the concentrate toward 35 the discharge edge, due to the vibration, will be accelerated by gravity.

It is a further object of the invention to so 40 construct the table that the discharge edge for the concentrates will be closely adjacent to the line of flow of the gangue or tailings.

The invention is hereinafter more fully described and claimed.

In the accompanying drawings forming 45 a part of this specification, Figure 1 is an elevation of my improved table, looking toward the elevated end of the same; Fig. 2 is a top plan view of the supporting and vibrating mechanism; Fig. 3 is a top plan view of the table; Figs. 4, 5, 6, and 7 are sectional views on planes indicated respectively by the lines IV—IV, V—V, VI—VI, and VII—VII. Fig. 3 and Fig. 8 is a detail view 50 showing means for operating table adjusting shaft.

55 In the practice of my invention the table 1 is supported as is customary by two main

or central posts 2 and by two pairs of adjusting posts, 3 and 4, arranged on opposite sides of the line of central posts and preferably adjacent to the upper and lower ends of the table as shown in Fig. 2. The upper ends of all of the posts have circular sockets for the reception of the semi-circular blocks 5, secured to the under side of the table. The central posts 2 have eyes 6 for the reception of the short shafts 7, supported by the channel bars 8, which also form the supports for the mechanism employed for vibrating the table as hereinafter described. The lower ends of the posts 3 and 4 fit 60 loosely in sockets carried by blocks 9 and 10 having their under faces inclined and resting on oppositely inclined upper faces of movable blocks 11 and 12. The latter blocks are connected to arms 13 and 14 secured to the adjusting shaft 15. These inclined blocks or wedges are so arranged that when the shaft is rotated one end of the table will be raised while the opposite end is lowered an equal distance. This shaft is 65 rotated to adjust the table by a threaded rod 16 engaging the outer end of an arm 17 secured to the shaft as shown in Figs. 2 and 8. In its vibrations the table is moved in one direction by a spring 18 bearing at one end 70 against an abutment 19 secured to the table, and at its opposite end against a plate 20, carried by the threaded rod 21, which passes through an internally threaded sleeve carried by the channels 8. The opposite movement of the table is effected by a crank pin 22 eccentric to the driven shaft 23, and a lever 24 having a concave portion in which the pin 22 operates. A roller is loosely mounted 75 on the pin, so that there will be a small downward slip of the lever as the pin engages it, thereby modifying the abruptness 80 of the reversal of the table. This lever is provided with an upwardly projecting arm 25 adapted to engage the edge of the table 85 through the medium of a bearing block 26. 90

The slime or pulp is run into a box 27 provided with openings in line with the radiating channels of the distributor 28, which is constructed and arranged to discharge the slime onto the table along the entire length of its upper edge or head. It will be observed that the direction of vibration of the table, as indicated by arrow *e*, is substantially at right angles to the initial direction of the flow of the slime, as indicated by arrow *f* in Fig. 3, consequently 100 105 110

for a given inclination of the table the direction of flow of materials composing the slime will be modified or changed proportionally to the rapidity and force of the 5 shocks imparted to the table and the specific gravities of the materials composing the slime, and the resultant flow of the material will be at an angle more or less acute, to the direction of vibration. Obviously, the 10 greater the specific gravity the more acute the angle of its resultant flow to the direction of vibration, and by properly proportioning the length of the table, its inclination, and the rapidity of the shocks imparted thereto, the light and heavy ingredients, *i. e.*, the gangue and concentrates, of the slime may be made to discharge over different portions of the edge of the table. As the slime flows down along the table, the 15 heavier ingredients, *i. e.*, the concentrates or values, will settle down toward or onto the surface of the table, and unless provision is made for checking or retarding such heavier material, the latter will be carried along to 20 a greater or less extent with the lighter superincumbent ingredients and a considerable proportion of the concentrates will pass away with the gangue at the lower end of the table. The retardation of the concentrates is effected by means of "waves" 25 formed on the surface over which the slime flows. These waves are usually formed by strips 30 of wood or other material placed underneath the linoleum or other fabric forming the surface of the table. These 35 waves have heretofore been arranged at, or approximately at right angles to the initial flow and also substantially parallel with the direction of vibration, so that after being caught by a wave the movement of the 40 concentrates toward the front edge of the table is due almost entirely to the shocks imparted to the table. In my improved table, the waves are arranged as shown in Fig. 3 at an 45 acute angle to the initial direction of flow and to the direction of vibration of the table. And further the waves or ripples and the means for feeding the slime have been constructed and arranged heretofore, in such 50 relation to each other, that all the values even such as may be deposited on the table above the first wave or riffle are compelled to move upwardly and over a number of ripples or waves before the values reach the 55 discharge edge. In my improved table, provision is made for feeding the slime in between adjacent waves or ripples, which extend from the head of the table toward or to the edge over which the values or concentrates are finally discharged. Hence any 60 values deposited on the table before the slime passes over a wave or riffle will be diverted toward the discharge edge by the wave or riffle against which they may lodge, 65 and will not be compelled to move over one

or more waves or ripples to reach such edge. In other words a very large percentage of the values in the slime will have after separating from the gangue, an unobstructed path to their discharge edge. As it may not be desirable to have a long concentrate discharge edge, the lower ends of some of the waves or ripples above which the slime is fed will be above such discharge edge, and in such cases these waves or ripples will be 70 shortened so as to leave a space adjacent to the portion *a* of the rim 31 extending from the concentrate discharge edge around to the lower end of the table. This clear or unobstructed space *b* extends down to the 75 discharge edge 33. It is preferred that all of the waves or ripples above which slime is fed should be at such an angle as to terminate above the lower end of the discharge edge 33. As there will be a deposit of values 80 at all points of the table, the latter should have waves or ripples over its whole surface and hence a portion of such waves are necessarily so located that concentrates lodging against them will be directed, some toward 85 the gangue discharge edge 32 and some to one side of the latter, or toward the lower end of the table. The latter concentrates and the gangue flowing to one side of the gangue discharge edge 32 are deflected by 90 the portion *c* of the rim toward the discharge edges 32 and 33. To prevent the discharge of concentrates deflected by the rim and some of the waves toward the gangue edge 32, over such edge, a riffle 34 is so 95 placed adjacent to such edge as to direct the concentrates to the adjacent mineral edge. In order to prevent a splashing of the gangue as it strikes against the portion 100 *c* of the rim, the surface intermediate the lower ends of the waves and the rim portion *c* is given an upward inclination as shown at 35 in Figs. 4 and 6. As will be readily understood, the waves will tend to deflect the flow of the concentrates toward the discharge edge and thereby shorten their movement across the table, and to that extent increase the efficiency of the table. This tendency to direct the movement of the concentrates toward the discharge edge is increased 105 by the vibratory movement imparted to the table as hereinbefore stated. It will be understood that the movement of the values or concentrates to the mineral edge which forms a part of the front side of the table 110 should be as direct and short as possible, but this movement should be out of the line of flow of the gangue. In order to divert the gangue away from the movement of the values, the side of the table having the 115 mineral discharge edge is adjusted slightly higher than the opposite or rear side. This elevation should be sufficient to a little more than counterbalance the diverting influence of the waves and vibrations on the lighter 120

125

130

ingredients or gangue, but should not be sufficient to materially affect the movement of the concentrates due to the vibration or gravity, toward the mineral discharge edge. 5 By giving the table the proper inclinations, longitudinally and transversely, the pulp will tend to flow down and away from the mineral discharge edge, or toward the left in Fig. 3, and at a very acute angle across 10 the waves. At the same time, the general direction of movement of the concentrates will be toward the mineral discharge. Some of the concentrates will move along the upper sides of the waves and some will cross 15 the waves, but at a very obtuse angle to the waves, and the point of crossing each succeeding wave will be nearer the right hand side of the table, and also to the mineral discharge edge. Thus from the time the 20 pulp is discharged onto the table there is not only a vertical separation of the ingredients, due to difference in specific gravity, but also a longitudinal separation of the lighter and heavier ingredients. The 25 lighter materials tend to flow by gravity toward the left hand or rear side of the table in Fig. 3, or at least are prevented from following the heavier material or concentrates as they move to the right toward 30 the front side of the table having the mineral discharge edge. There is no tendency or opportunity of the lighter and heavier ingredients flowing together after separation has begun, except for the small quantity 35 of concentrates which may after separation from the gangue, pass across the waves or riffles and the comparatively small quantity which moves down onto the surface 35 at the lower end of the table. This 40 small amount of concentrates will move along the surface 35 with the gangue until the discharge edge 32 is reached, when the concentrates will be retained by the riffle 34 and directed toward the mineral discharge 45 edge 33. Diverging lines of flow of the gangue and concentrates are initiated as soon as the pulp begins to flow along the table, the gangue moving downward toward the lowest corner, due to the inclination of 50 the table, and the concentrates moving downward to the right along the waves or riffles. The divergence of the gangue from a direct line of flow toward the lower end of the table, causes it to move farther and 55 farther from the concentrates discharge edge. By properly adjusting the inclination of the table the right hand edge of the stream of gangue which is indicated by a dotted line X will intersect the gangue discharge edge 32 some distance from the concentrate discharge edge, as shown in Fig. 3. 60 Any movement of the values or concentrates along the table after they have passed from under the gangue is useless and hence in my 65 improved table, it is possible to so arrange

the concentrate discharge edge and the pulp feeding means relative one to the other, that a portion of the pulp will be fed onto the table in advance (or to the right in Fig. 3) of the mineral discharge edge. This position of the mineral discharge edge relative to the feed of the pulp will be made clear by drawing a line from the upper end of the mineral discharge edge at right angles to the direction of vibration of the table. It 70 will be seen that if this line be extended to the head of the table it will cross the line of feed of the pulp a considerable distance from the right hand end of the feed, and that a substantial portion of the pulp is fed 75 onto the table at points in advance of the mineral discharge edge, whereas it has heretofore been the practice to so construct the tables, that the mineral discharge edge is necessarily a considerable distance ahead of 80 the feed of the pulp, in order to obtain an effective separation of the values and gangue. It is characteristic of the operation of my improved table that the values having once settled out of the gangue will not be 85 again mingled therewith but move directly to the mineral discharge edge. By reason of 90 this effective separation it is possible to reduce the length of travel of the values. As shown in Fig. 7, the waves may have their 95 upper sides considerably steeper than the lower sides.

As is well known in the art, some of the values are in such a fine state of division as to render their separation from gangue 100 slow and difficult, and are influenced only to a slightly greater degree than the gangue by the vibrations of the table. A small percentage of these fine concentrates will flow with the gangue down onto the surface 105 35 and, being diverted by the portion e of the rim, will move toward the gangue discharge edge 32. As the table has a slight inclination, the movement of the fine concentrates from behind the riffle 34, by 110 which they are caught as the gangue flows over the riffle, must be effected by the vibratory action. The reduction of width of the lower end of the table due to the location of the mineral discharge edge in the 115 rear of the feed of pulp, hereinbefore described, will prevent a piling up of the concentrates behind the riffle 34, it being impracticable to move such concentrates with any degree of rapidity or for any considerable distance by the vibratory movement of the table. By thus cutting back the mineral discharge edge, there will be a very short travel of the fine concentrates collected by the riffle. This cutting back of the 120 mineral discharge edge is advantageous also as regards the coarser concentrates, which will begin to settle down onto the table as soon as the pulp is run onto it. These 125 heavier values will readily move to the 130

right in Fig. 3, and, the discharge edge being cut back, will be discharged nearly as soon as they have moved out from under the lighter gangue.

5 It will be understood that a water box for the final clean up of the concentrates may be suitably arranged relative to the mineral discharge edge, as is customary in the art.

10 It is characteristic of my improvements that the waves or riffles are uninterrupted or continuous across the table, so that nearly all concentrates or values once deposited on the table above a riffle will remain there until discharged over the mineral edge. Of course some of the very fine concentrates will pass over the riffles above which the pulp was fed, but the quantity will be small. It has been found that where 15 the values pass over the riffles, such a large amount will collect against the lower riffles as to greatly reduce the effectiveness of the 20 table.

I claim herein as my invention:

25 1. In a slime concentrator, the combination of a table having a mineral discharge edge in its front side, and inclined downwardly from its head and upwardly from its rear side, continuous or unbroken riffles, 30 extending from the head diagonally across the table toward the front side thereof, means for feeding pulp directly into the channel intermediate the riffles, means for the direct discharge of values from the table 35 at the termination of the riffle channels extending from the point of feed, and means for so vibrating the table that the values will move along the riffles and away from the rear side of the table.

40 2. In a slime concentrator, the combination of a table having a mineral discharge edge in its front side and inclined downwardly from its head and upwardly from its rear side, having a gangue discharge at 45 its lower end continuous or unbroken riffles originating at points along the line of feed of the pulp, and extending diagonally across the table and terminating above the gangue discharge edge and adjacent to the 50 front edge of the table, pulp feeding means extending along the head of the table and adapted to discharge the pulp into channels formed by the riffles, and means for so vibrating the table that the values will move 55 upwardly along the riffles.

3. In a slime concentrator, the combination of an inclined table, means for vibrating the table, means for feeding pulp onto

the table along its head or upper end, riffles extending continuously from the points of feed diagonally across the table toward the mineral discharge edge, said edge being in the rear of a line drawn at right angles to the direction of vibration of the table from the upper end of the mineral discharge edge 65 to the head of the table.

4. In a slime concentrator, the combination of an inclined table having mineral and gangue discharges adjacent and at an angle to each other, means for vibrating 70 the table, means for feeding pulp onto the table along its head or upper end, riffles extending continuously from the points of feed diagonally across the table toward the mineral discharge edge, the junction of the 75 discharge edges coinciding with a line at right angles to the direction of vibration, of the table and intersecting the line of feed of the pulp at a point in the rear of the 80 upper corner of the table.

5. In a slime concentrator, the combination of an inclined table having mineral and gangue discharge edges at an angle to each other, continuous or unbroken riffles extending from the head and rear edge of 85 the table diagonally across the same toward the discharge edges, means for feeding pulp into the channels intermediate the riffles terminating above the lower end of mineral discharge edge, and means for vibrating the 90 table.

6. In a slime concentrator, the combination of an inclined table having mineral and gangue discharge edges adjacent and at an angle to each other, continuous or unbroken riffles extending from the head, and rear edge of the table diagonally across the same toward the discharge edges, means for feeding pulp into the channels intermediate the riffles terminating above the lower end 100 of the mineral discharge edge, the other riffles terminating above the lower end of the table thereby providing a space having a uniform surface extending to the gangue discharge edge, a retaining rim extending 105 along the lower end of the table to the gangue discharge edge and a riffle arranged adjacent to the gangue discharge edge and extending to the mineral discharge edge.

In testimony whereof, I have hereunto set 110 my hand.

WILLIAM F. DEISTER.
